COMBINED CONTAINER AND HOLDER FOR ADHESIVE AND APPLICATOR

Charles W. Lofgren, Oak Park, Ill., assignor, by mesne
assignments, to Sanford Research Company, a corpo-
ration of Illinois

Filed May 2, 1962, Ser. No. 69,931

Term of patent 14 years

(Cl. D58—17)

FIGURE 1 is a top perspective view of a combined container and holder for adhesive and applicator showing my new design; and

FIG. 2 is an exploded top perspective view thereof. The portions shown in broken lines are for illustrative purposes only.

The characteristic feature of my design resides in the combination with the cover of a centrally disposed upstanding and generally cylindrical imperforate projection forming an internal recess, and a laterally projecting tab of the configuration substantially as shown.

I claim:

The ornamental design for a combined container and

holder for adhesive and applicator, as shown and described.
